ATTORNEY

UNITED STATES PATENT OFFICE

WILLIAM B. HOLLINGSHEAD, OF MOUNT VERNON, NEW YORK

SOUND-DAMPING DEVICE

Application filed August 30, 1919, Serial No. 320,786. Renewed March 13, 1929.

This invention has reference to sound boxes for sound-recording and reproducing machines, and the objects of the invention are to provide a device of this character which will record and reproduce the true tonal characteristics and at the same time will be of practical and relatively inexpensive construction.

Special features of the invention relate to the control of the sound vibrations so as to gain true reproductions of the original sounds with the full harmonics and overtones.

In the accompanying drawing, I have illustrated various embodiments of my invention, but would have it understood that the invention is not limited to these particular disclosures.

In the drawing referred to, Figure 1 is a face view of one form of the sound box, the neck of the sound box and the stylus bar being indicated as broken away; Figure 2 is a vertical sectional view on substantially the plane of line 2-2 of Figure 1; Figures 3 and 4 are views similar to the first two figures of another form of the invention; likewise Figures 5 and 6, and 8, 9 are similar views of two other forms of the invention; Figure 7 is a graphic reproduction of the damping effect obtained with the construction disclosed in Figures 5, 6; Figure 10 is an enlarged sectional view of a further development of a modification illustrated in Figure 9; Figure 11 is a face view of another form of the sound box; Figure 12 is a detailed view of a special form of mounting for the stylus bar.

15 designates a sound-box casing which may be of the open construction illustrated in Figures 2, 4 and 9, or may be closed at the back as indicated at 16 in Figure 6. The casing is provided with a suitable neck portion 17 by which it is attached to the sound-vibration-transmitting arm (not shown), and which arm may be of the construction disclosed and claimed in co-pending applications of mine. This casing is usually constructed of a heavy and relatively "dead" material such as lead.

50 18 designates the diaphragm which may

be made of iron or steel or other suitable material. 19 designates the stylus bar which may be connected with the central part of the diaphragm in the usual way, but which in a preferred construction is connected 55 with the diaphragm as indicated at 20 in Figure 11, that is, near one edge and at a distance anywhere from the edge substantially equal to one-ninth of the diameter of the diaphragm. I find that the connection 60 of the stylus at this point does away with certain objectionable elements in tone reproduction and produces superior results, due possibly to the relation of this point to the nodal characteristics of the diaphragm. 65

In the first form illustrated, a control of the vibration effects is obtained by applying a sectoral damping-element 21 over the upper sectoral portion of the diaphragm and by providing a cover 22 of greater area over 70 said damper. This cover not only shields and conceals the damper but apparently adds a somewhat mellow and improved tone to the apparatus.

In the form shown in Figures 3 and 4, 75 two sectoral dampers 23 are applied to the face of the diaphragm at opposite sides of the center thereof, said dampers being substantially in the form of quadrants. These damping elements may be in the form of 80 adhesive fabric or fabric adhesively applied to the diaphragm.

Similarly, in the constructions illustrated in Figures 8, 9 and 10 the damping elements may be in the form of adhesive fabric, said elements consisting in these latter disclosures of a series of plies or superposed discs 24 applied either to one (Figures 8, 9) or both (Figure 10) faces of the diaphragm. 85

I find that particularly quick results are 90 obtained if the diaphragm is considered as divided into sectors corresponding in number to eight, or multiples of eight, and the corresponding dampers are applied to the sectors in such relation. In Figures 5 and 95 6 I have indicated a diaphragm as divided into sixteen sectors and have shown alternate sectors 25, 26 as engaged by damping plugs 27, 28 respectively. These spaced plugs are shown as carried by a slide 29 100

circumferentially adjustable within a slot or annular guideway 30 provided in the ring member 31 which is secured to the face of the sound-box casing. By means of this construction the damper may be adjusted circumferentially about the peripheral portion of the diaphragm to bring the damping elements into engagement with any two alternate sectors desired; and this slide can be easily adjusted until the best effect is obtained. This damping effect is indicated graphically in Figure 7 where alternate sectoral portions 25 and 26 are designated as the crests of waves 25' and 26' from which it will appear that the dampers 27-28 check the vibrations of these sectors, while leaving the other sectors free to vibrate.

In Figure 12 the stylus bar 32 is shown as looped about the diaphragm and as connected therewith by simple contact at the point 33, the mounting of the bar at 34 exerting sufficient tension to hold the bar properly engaged with the face of the diaphragm.

I claim:

- 25 1. A sound-box casing, a diaphragm mounted in said casing, a ring carried by said casing and having an annular slot therein and a vibration-controlling member adjustably engaged in said slot, and engaging the diaphragm.
2. A sound-box casing, a diaphragm mounted in said casing, a ring carried by said casing and having an annular slot therein and a vibration-controlling member adjustably engaged in said slot, and provided with separated projections for engagement with the diaphragm at different spaced portions of the surface thereof.

In testimony whereof I affix my signature.

40 WILLIAM B. HOLLINGSHEAD.
